BOTTLE

Martin Schnur, Short Hills, and Mel Appel, Murray Hill, N.J., assignors to Celanese Corporation of America, New York, N.Y., a corporation of Delaware

Filed Sept. 9, 1963, Ser. No. 76,525

Term of patent 14 years

(Cl. D58—8)

The rear and side not shown are substantially like the front and side shown.

The dominant features of our design reside in the portions shown in full lines.

We claim:

The ornamental design for a bottle, as shown and described.
